CLAIM

The ornamental design for a silencer tube body, as shown and described.

DESCRIPTION

FIG. 1 is a front perspective view of the silencer tube body of the present invention;

FIG. 2 is a top plan view thereof;

FIG. 3 is a front view thereof;

FIG. 4 is a rear view thereof;

FIG. 5 is a left-side view thereof; and,

FIG. 6 is a right-side view thereof.

The broken lines are for purposes of illustrating portions of the silencer tube body that form no part of the claimed design.
